UNITED STATES PATENT OFFICE.

ALFRED CROOK, OF PHILADELPHIA, PENNSYLVANIA, ASSIGNOR TO PHILADELPHIA ROLL & MACHINE COMPANY, OF PHILADELPHIA, PENNSYLVANIA, A CORPORATION OF PENNSYLVANIA.

VARIABLE STATISTICAL CHART.

1,360,726.

Specification of Letters Patent. Patented Nov. 30, 1920.

Application filed August 27, 1919. Serial No. 320,173.

To all whom it may concern:

Be it known that I, ALFRED CROOK, a citizen of the United States, residing at Philadelphia, in the county of Philadelphia and State of Pennsylvania, have invented 5 certain new and useful Improvements in Variable Statistical Charts, of which the following is a specification.

This invention relates to an improved 10 weight and price chart, designed particularly for use in connection with the manufacture of standard articles, and adapted in such use, following the adjustment of the chart in accordance with predetermined 15 requisites of such article, say the diameter and length, to automatically display all desirable data relative to the weight and price of the article of such predetermined requisites.

20 The improved chart is made up of a casing, within which is slidably arranged a plurality of slides. The casing is formed with suitably arranged apertures, and the slides provided with predetermined data 25 for cooperation with the apertures in the casing, and also with openings to determine the display of data on other slides through the casing apertures.

The specific article permits the user, 30 when the chart has been adjusted for the predetermined requisites of the article, to have before him data relative to the weight and prices of that particular article, exactly as if a specific list had been prepared for 35 that article. This enables the manufacturer to determine without delay all necessary information for a customer.

The invention is illustrated in the accompanying drawings, in which:

40 Figure 1 is a face view of the improved chart, the slides being in normal or non-display positions.

Fig. 2 is a similar view, the slides having been adjusted to one position.

45 Fig. 3 is a plan of the reverse face of the chart, the slides being shown in an adjusted position.

Fig. 4 is a section on line 4-4, Fig. 3.

Fig. 5 is a section on line 5-5, Fig. 3.

50 Fig. 6 is a view in plan of one of the slides.

Fig. 7 is a similar view of another and corresponding slide.

Fig. 8 is a broken perspective view of the casing.

Figs. 9 and 10, are respectively, opposite face views of an intermediate slide.

The invention is here shown and will be described as designed for a weight and price chart in the manufacture of metal rolls, and 60 comprises a casing 1, including opposing face walls 2 and 3, and edge walls 4, to thus provide a substantially rectangular envelop-like casing, within which the slides are 65 movable.

In the particular instance shown, the face walls are duplicates, each bearing a diagrammatic outline of the article for which the chart is designed, in this instance a roll, as at 5. Within the outline of the body of 70 the roll, the face wall is formed with an aperture 6, marked to indicate the diameter of the body, and above such body outline, there is formed another aperture 7, marked to indicate the length of the body. Within 75 the outline of the article and on the neck and pod portion of the article, the face wall is formed with apertures 8 and 9, here shown for convenience as a single aperture, marked respectively to indicate the diameter 80 of the neck and pod portion of the roll. Above the opposite neck and pod portion of the outline, the face wall has apertures 10 and 11, indicated for the length of the pod and neck.

Above the roll outline 5, each face wall is 85 formed with an elongated slot 12, marked to indicate the weight of the roll, this slot being substantially of the length of the roll outline 5. Immediately below the outline 90 5, are formed two apertures 13 and 14, the first marked to indicate the weight of the necks and pods of the roll, and the second marked to indicate the weight of one inch of 95 the roll body.

The apertures so far described will disclose data concerned with the weight and measurements of the roll and parts thereof, but the chart is also adapted to indicate prices based on the other details disclosed. 100 For this purpose each face wall is further formed with several apertures, more or less grouped below the outline 5. These price apertures are here shown as a transversely aligned group of four apertures, 15, 16, 17, 105 and 18, marked respectively to indicate the

price of the necking for one roll, in sand, at 15, and in chill, at 16; and the price of turning per pound in sand, at 17, and in chill, at 18. Below the price apertures noted, are 5 transversely alined apertures 19 and 20, indicating the price of rough roll castings, 19 indicating the price in sand per pound, and 20 indicating the price per pound in chill. Below these apertures 19 and 20 is a single 10 aperture 21, marked to indicate the rate per hour for turning grooved or special rolls.

The casing 1 is preferably divided by longitudinal partitions 22, extending inwardly a short distance from the edge walls 4, to 15 permit sliding movement of the various slides without interference. In the present adaptation of the invention three slides are provided, a main slide 23 and auxiliary slides 24 and 25, the latter being identical, 20 except as to data thereon. The main slide, which is positioned between the auxiliary slides, is divided on each surface into a series of vertical columns 26 for weight data, and a single column 27 for data indicating the length of the roll body. The columns 26 and 27 on the respective sides of the main slide are for identical uses, except that the data on one side is for rolls up to a certain diameter, as noted on the face wall 25 of the casing, while the data on the opposite side of the main slide is for rolls above such diameter.

The columns 27 are so positioned that the data thereon will be visible through the 35 aperture 7 of the face of the casing, that is the aperture for data indicating the length of the body of the roll. The data on the beginning columns 26 of the main slide are to be exposed through the roll-weight indicating slot 12, in accordance with the position of the particular auxiliary slide, as will be explained.

The auxiliary slides are in general duplicates, each being formed in the upper portion with a series of column-wide progressively stepped apertures 28, adapted for successive registry with the weight-indicating slot 12 of the casing, as the auxiliary slide is progressively adjusted to permit the appropriate data on the columns 26 of the main slide to be visible through such slot 12. The auxiliary slides are also each formed with a column-wide elongated slot 29, adapted to at all times register with the aperture 7 50 of the casing, in order that the data of column 27 of the main slide may be visible through such aperture 7. The remaining columns 30 on the auxiliary slides are marked with appropriate data to register 55 with the remaining apertures in the face walls of the casing, as such auxiliary slide is adjusted. This data is of course arranged with particular reference to the article and size indicated through the appropriate apertures, so that for any size noted through the

appropriate apertures, the data of the remaining apertures will properly correspond.

In use, with the various slides in normal positions in the casing, no data will be visible through the apertures of the casing. Assuming that data relative to a roll having a diameter of eight (8) inches through the body and a length of sixteen (16) inches are required. The auxiliary slide of lower dimensions is first adjusted by longitudinal movement in the casing, as by thumb-piece 31, until the figure 8 appears in the aperture 6, that is the roll-diameter aperture, whereupon the remaining apertures, except the aperture 7 and slot 12, will expose data on 80 the adjusted slide giving the appropriate information indicated at each slide for this particular roll. The movement of the auxiliary slide has positioned one of the apertures 28 in registry with the slot 12, so that 85 the main slide is exposed. The main slide is now adjusted until the required body length of the roll, that is sixteen (16) inches appears in the aperture 7. Following this adjustment, the weight of the particular roll 90 will appear in the slot 12, through the alined aperture 28 of the auxiliary slide, this data being that on the columns 26 of the main slide.

In the present instance, the chart is made 95 up to simulate the article for which it is designed to indicate weight and price, though this is an unessential detail of the present invention.

The important feature of the invention is 100 the provision, through the adjustment of but two slides, of all necessary data in connection with an article having certain predetermined characteristics, that is, in the present instance, a roll of certain length and diameter of body. With the slides adjusted in accordance with these details, all other necessary manufacturing information relative to weight and cost is automatically disclosed, and hence the time otherwise required to 105 compute this data for each particular roll is saved.

Having thus described the invention, what is claimed as new, is:—

1. A price and weight chart having a casing formed in opposed faces with apertures, a main slide within the casing and bearing distinctive groups of data, and auxiliary slides arranged within the casing on each side of the main slide, the auxiliary slides having data to be exposed through the casing apertures and being formed with apertures to control the exposure of the data on the main slide.

2. A price and weight chart for standard 125 articles, comprising a casing having a slot marked to indicate the weight of the article and having apertures marked to indicate the dimensions of the article, and slides operable in the casing, one of said slides having 130

data to register with the weight-indicating slot and with one of the dimension-indicating apertures, the other slide having data to register with other dimension-indicating 5 apertures and formed to control the data of the first slide displayed through the weight-indicating slot.

3. A price and weight chart, comprising a casing formed with a slot and apertures, a 10 main slide operable within the casing and having data to register with one of said apertures and with the slot, and an auxiliary slide operable within the casing and having data to register with the remaining 15 apertures, said auxiliary slide having apertures to register with the slot in any position of such slide to control the data of the main slide exposed through said slot.

4. A price and weight chart for rolls having a casing formed with a roll-weight indicating slot, roll-dimension indicating apertures, and price-detail indicating apertures, 20 and slides adjustable within the casing and

bearing data to be exposed through the dimension-indicating apertures in accordance 25 with the required dimensions of the article, said slides also bearing additional data to be exposed through the weight-indicating slot and price detail apertures in such casing.

5. A chart comprising a casing with defined apertures to indicate distinct dimensions of an article and a defined aperture to indicate the weight of the article, a slide having dimension-data to register with one of the dimension apertures of the casing and 35 a series of different weight indications adapted to simultaneously register with the weight-indicating aperture, and a second slide having dimension data to be registered with the remaining dimension aperture and 40 performed with a slot to register with and permit the exposure of a single one of the weight indications of the first slide in registry with the weight indicating aperture.

In testimony whereof I affix my signature. 45
ALFRED CROOK.
